UNITED STATES PATENT OFFICE.

EDWARD ERICKSON, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

HEEL-BEADING MACHINE.

1,315,218.

Specification of Letters Patent. Patented Sept. 9, 1919.

Application filed March 4, 1916. Serial No. 82,095.

To all whom it may concern:

Be it known that I, EDWARD ERICKSON, a citizen of the United States, residing at Beverly, in the county of Essex and State 5 of Massachusetts, have invented certain Improvements in Heel-Beading Machines, of which the following description, in connection with the accompanying drawings, is a specification, like reference characters on 10 the drawings indicating like parts in the several figures.

My invention relates to burnishing machines and particularly to machines used in the ornamentation of boots and shoes. In 15 the manufacture of boots and shoes it is customary to burnish, bead or indent lines of ornamentation upon the edges of various parts of them. It is the object of my invention to provide a machine whereby the 20 edges of the heels of shoes can be easily and satisfactorily ornamented.

A feature of my invention is a tool carrier having an ornamenting gage and an ornamenting tool mounted thereon. The engagement of the ornamenting gage with one 25 corner face of a heel ornaments this face while gaging the operation of the ornamenting tool on the adjacent corner face.

Another feature of the invention is a 30 novel organization of ornamenting mechanism operating by percussive action on the shoe. It has been found advantageous to make lines of indentation by percussive rather than by frictional treatment with a 35 tool.

Another feature of my invention is an ornamenting tool having an ornamenting gage and an adjustable ornamenting tool, whereby both edges of a corner of a heel 40 may be ornamented, and the width of an ornamented portion may be varied.

These and other features of the invention comprising various combinations and arrangements of parts will be best understood 45 and appreciated from the following description of a preferred embodiment thereof selected for purposes of illustration and shown in the accompanying drawings in which,

50 Figure 1 is an elevation of the head of the machine,

Fig. 2 is a detail, the supporting parts of the machine being removed,

Fig. 3 is a detail of a burnishing tool,

Fig. 4 is a view of a beading wheel, and 55 Fig. 5 shows two views of a modified form of burnishing tool.

The head 1 carries a shaft 2 which is power driven by means of a pulley 3. The head contains two sockets 4 and 5 opposite 60 the inner ends of which are flattened portions 6 and 7 of the shaft 2, respectively. These flattened portions may be made continuous with each other, if desired. The socket 4 contains the tool shank 8 which is 65 so arranged that it can reciprocate vertically in the socket but is confined by a shoulder at its lower end so that it cannot fall out. The shank 8 carries a burnishing tool on its lower end.

70 The burnishing tool, shown more particularly in Fig. 3, has a body 9 in which there is a right and left screw 10 extending laterally from both sides. The screw carries a disk 10^a which is seated in a slot 10^b in the 75 body. Threaded on the ends of this screw are two ornamenting plates 11 which are doweled at 12 to permit their lateral adjustment with regard to the head and to prevent their turning. The dowels 12 also 80 prevent the screw and plates from sliding out of the head, by means of the slot 10^b. A set screw 13 holds the screw 10 in adjusted position. At the bottom of the head 9 is the combined gage and burnisher 14. As 85 shown in Fig. 3 this gage does not cover the entire bottom face of the head 9 but leaves over-hanging portions 15 of the plates 11. When a heel is presented to the tool as in Fig. 2 the upward pressure of the work 90 lifts the shank 8 against the shaft 2 and the flattened portion 6 thus causes a rapid up and down reciprocation of the shank 8. The member 14 burnishes the ends of the heel breast and at the same time serves as a 95 guide for the plate 11 which indents a line along the outside vertical edge of the heel adjacent to the breast. The portion 15 of the plate 11 ornaments the sole above the breast at the end of the shank, the overhang permitting the portion 15 to reach these parts of the shoe while the gage 14 is 100 in contact with the breast.

The other lateral edge of the heel breast is treated by rotating the shoe around an 105 axis perpendicular to its sole and applying the other edge of the heel breast to the other side of the tool carried by the shank 8.

The lateral adjustment of the plates 11 permits any desired variation in the distance of the indented line from the corner of the heel breast.

5 In the alternative construction of tool shown in Fig. 5 the body 16 has the indenting surface 17 on its lower end and has hinged to it the guide and burnisher 18. This guide and burnisher is held in adjusted position by a screw 19 which works against a spring 20. It will be noticed that there are two overhanging portions 21, one on each side of the guide 18. When this form of tool is used the shoe is rotated about 10 its longitudinal axis and the heel breast is always presented to the same side of the gage 18.

At the extremity of the head of the machine is mounted, upon a horizontal pivot 20 22, an arm 23. On the inner end of this arm is carried the plunger 24 which is vibrated in the socket 5 by the flattened portion 7. The outer end of the arm carries the tool 25. This tool is similar to the tool 25 shown in Fig. 5 except that a beading wheel 26 takes the place of the edge 17. The arm 23 is so balanced that the plunger 24 is not in contact with the shaft 2 except when under the upward pressure of the work. The tool 25 is then vibrated vertically about the pivot 22 as center. The end of the shaft 2 carries a crenelated wheel 27 and an idler gage 28 for indenting a line across the tread face of the heel as shown in Fig. 4.

35 Having described my invention, what I claim as new and desire to secure by United States Letters Patent is:—

1. A tool carrier constructed and arranged to reciprocate transversely to the work and carrying an ornamenting gage and an ornamenting tool.

2. A tool carrier constructed and arranged to reciprocate transversely to the work and carrying an ornamenting gage 40 and an ornamenting tool mounted laterally thereof.

3. An ornamenting tool having a burnishing guide constructed and arranged to move across a heel edge and an adjustable ornamenting tool mounted laterally of the burnishing guide in such manner that both 50 faces of a heel edge may be simultaneously treated.

4. An ornamenting tool comprising a burnishing guide adapted to engage the edge of

a heel breast and a laterally adjustable ornamenting tool projecting beyond said guide in such manner that the sole edge at the end of the shank may be ornamented.

5. In a machine of the class described, a lever having a tool at its end, said lever and its tool being constructed and arranged to permit a shoe to be turned freely over or about while in contact with the tool, and means for applying percussive impulses to the lever, said lever being normally separated from its actuating means and shiftable to receive percussive impulses when the work is pressed against the tool.

6. In a machine of the class described, an ornamenting tool adapted to be percussively engaged with the work and a relatively adjustable burnishing guide.

7. In a burnishing machine, a tool having a gage constructed and arranged to burnish one edge of a corner of a heel and a surface constructed and arranged to ornament the other edge of said corner, and means for oscillating said tool transversely to the portion of the work being treated.

8. In an ornamenting machine, a tool having an ornamenting guide, an ornamenting element adjacent said guide, with a portion overhanging said guide and means for oscillating said tool with the ornamenting guide in contact with the edge of a heel breast corner whereby the ornamenting element may treat the other edge of the corner and the sole edge adjacent the heel breast, whereby both edges of a heel corner may be ornamented.

9. In an ornamenting machine, a rotating shaft, and a member oscillated by said shaft in a path lying across the axis of the shaft, said member carrying an ornamenting tool.

10. In an ornamenting machine, a moving shaft, an ornamenting tool on the end of said shaft, and a second ornamenting tool operated by said shaft and positioned outside the end of the shaft in a direction 100 parallel to the shaft.

11. In a machine of the class described, a moving shaft, an ornamenting tool on the end of the shaft, and an arm overhanging the end of the shaft carrying an ornamenting tool, said arm being operated by said shaft.

In testimony whereof I have signed my name to this specification.

EDWARD ERICKSON.

It is hereby certified that in Letters Patent No. 1,315,218, granted September 9, 1919, upon the application of Edward Erickson, of Beverly, Massachusetts, for an improvement in "Heel-Beading Machines," an error appears in the drawings requiring correction as follows: The Figure 4 is incorrectly shown and should appear as below:

and that the said Letters Patent should be read with this correction therein that the same may conform to the record of the case in the Patent Office.

Signed and sealed this 11th day of November, A. D., 1919.

SEAL.]

M. H. COULSTON,
Acting Commissioner of Patents.
